UNITED STATES PATENT OFFICE.

GEORGE W. MURPHY, OF PHILADELPHIA, PENNSYLVANIA, ASSIGNOR TO INTERNATIONAL HARVEST HAT COMPANY, OF ST. LOUIS, MISSOURI.

HAT-CROWN-ADJUSTING DEVICE.

Application filed August 4, 1925. Serial No. 48,118.

To all whom it may concern:

Be it known that I, GEORGE W. MURPHY, a citizen of the United States, residing in the city and county of Philadelphia and 5 State of Pennsylvania, have invented certain new and useful Improvements in Hat-Crown-Adjusting Devices, of which the following is a specification.

This invention relates to a hat crown adjusting device for increasing or decreasing the crown, at its base, in a manner as desired by the wearer of the hat, and it is designed primarily for use in connection with harvest hats, but it is to be understood that a crown 10 adjusting device, in accordance with this invention, can be employed in connection with any style hat for which it is found applicable, and the invention has for its object to provide, in a manner as hereinafter set forth, an adjusting device including an adjustable band encircling the base of the crown of the hat and slidably connected therewith by a plurality of coupling members carried by the hat brim and providing 15 means for adjusting the base of the crown in a manner satisfactory to the wearer of the hat.

In most harvest hats there is considerable shrinkage and expansion due to climatic 20 conditions and due also to whether or not the wearer of the hat is perspiring. This causes the ordinary hat to shrink and expand, and it frequently occurs that on hot sultry days a farmer would prefer to have a 25 hat with loose fitting crown, whereas on account of the size of the hat and its light nature on a windy day a loose fitting hat would be readily blown off the wearer's head, and to provide for the taking up or expanding 30 of the base of the crown of the hat as best suits the wearer, is the primary object of this invention, and which is attained by providing an adjusting device of the band-like type positioned exteriorly of the crown 35 and connected to the brim of the hat in a manner as hereinafter referred to.

A crown adjusting device, in accordance 40 with this invention, as affecting a dealer, provides whereby a dealer does not have to 45 carry the same number of sizes in stock as he would have to do in case of hats not provided with the adjusting device in accordance with this invention, as the device can vary the size of the base of the crown to

form three to four different hat sizes, namely, 55 67 $\frac{1}{2}$ to 7 $\frac{1}{4}$ or vice versa.

Further objects of the invention are to provide, in a manner as hereinafter set forth, a hat crown adjusting device, which is simple in its construction and arrangement, 60 strong, durable, thoroughly efficient in its use, conveniently adjusted, enhancing the appearance of the crown, providing the hat band, and inexpensive to manufacture.

With the foregoing and other objects in view, the invention consists of the novel construction, combination and arrangement of parts, as hereinafter more specifically described and illustrated in the accompanying drawings, wherein is shown an embodiment 70 of the invention, but it is to be understood that changes, variations and modifications can be resorted to which come within the scope of the claims hereunto appended.

In the drawings wherein like reference characters denote corresponding parts throughout the several views:—

Figure 1 is a perspective view of a harvest hat, showing the adaptation with the crown and brim thereof of an adjusting device, in 80 accordance with this invention.

Figure 2 is a sectional plan of the crown.

Figure 3 is a section on line 3—3, Figure 1.

Figure 4 is an elevation of the buckle 85 forming an element of the device.

Referring to the drawings in detail, 1 denotes the brim, 2 the crown, and 3 the base portion of the crown of a hat.

The adjusting device, in accordance with 90 this invention, comprises a plurality of coupling members, as shown three in number, but this number can be increased or diminished. Preferably three coupling members are employed and each of which is referred 95 to generally by the reference characters 4, 5 and 6. Each of the coupling members is formed from a strip of flexible material 7, bent upon itself to provide a loop 8. One end of the strip 7 overlaps the other end, as 100 at 9, and the said overlapping ends are secured together by a row of stitching 10, which also secures the lower end of the coupling member to the upper face of the brim 1 at the inner portion thereof. Each coupling member extends upwardly and is positioned against the outer face of the base portion 3 of the crown 2. The coupling mem-

ber 4 is positioned at the vertical median of the front of the crown 2, the coupling member 5 at the vertical median of one side of the crown 2, and the coupling member 6 is positioned at the vertical median of the rear of the crown 2. Each of the coupling members, shown in Figure 3, is of curved contour so that it will abut against the base 3 of the crown, as well as the upper face of 10 the brim at the inner portion thereof.

The adjusting device further includes a hat band in the form of an adjustable strap 11 of flexible material which surrounds the base 3 of the crown 2 and is slidably connected in position through the medium of the coupling members. The strap 11 extends through the loops 8 and when positioned with respect to the base of the crown provides the band for the hat.

20 The strap 11 is bent upon itself to provide a pair of oppositely extending terminal portions 12, 13, which provide in connection with a buckle, to be presently referred to, a bow-like effect to one side of the crown 25 when the strap 11 is mounted in a position to form the hat band.

The buckle, which is referred to generally by the reference character 14, comprises a frame formed of a top and bottom bar 15, 30 16, a front end bar 17, a rear end bar 18, an apertured extension 19, projecting rearwardly from the bar 18, and a pair of intermediate bars 21, 22, which are offset outwardly with respect to the bars 17, 18. The bars 17 and 18 are spaced from each other and further positioned between the transverse center and the ends of the frame, thereby providing openings 22, 23 and 24.

40 The terminal portion 12 of the strap 11 extends through the opening 22, over the outer face of the bar 20, then inwardly through the opening 23 and under the bar 17, as well as projecting laterally therefrom. See Figure 2. The end terminal portion 45 13 of the strap 11 extends out through the opening 22 around the outer face of the bar 21, then inwardly through the opening 24 and under the bar 18, as well as projecting laterally therefrom. See Figure 2.

50 By increasing or diminishing the length of either one or both of the end portions 12 and 13, the base of the crown of the hat can be respectively taken up or expanded. As the strap 11 is slidably mounted in the 55 coupling members it can, when it is in the position shown in Figure 2, be bodily adjustable. The strap 11 is not directly secured to the crown 2 but is indirectly slidably connected therewith through the medium of the coupling members.

It is thought that the many advantages of a hat crown adjusting device, in accordance with this invention, can be readily understood, and although the preferred embodiment of the invention is as illustrated

and described, yet it is to be understood that changes in the details of construction can be had which will fall within the scope of the invention as claimed.

What I claim is:—

1. The combination with the crown and brim of a hat, of a series of upstanding, looped, spaced, narrow, endless coupling members, each forming in itself a complete loop and having its lower terminal portion fixedly secured solely to the inner portion of the upper face of said brim and the remaining portion free of connection with and arranged against the outer periphery of the base of the crown, said members positioned at the front, rear and one side of the crown, a slidable band in the form of an adjustable strap extending through all of said coupling members, positioned against parts of the sides, front and rear of the outer periphery of the base of the crown and free of direct connection therewith throughout, and a slide buckle bearing against a part of the outer periphery of the base of the crown and slidably engaging with and having portions of its outer face permanently overlapped by the free end terminal portions of the strap for adjustably connecting the ends of the latter together to vary the length of that portion of the strap between the ends of the buckle to vary the size of the base of the crown and further to bind said coupling members and strap against the outer periphery of the base of the crown.

2. The combination with the crown and brim of a hat, of an upstanding, looped, narrow coupling member positioned at the front, at the rear and at one side of the base of the crown, means for securing the lower end of each of said coupling members solely to the upper face of said brim in proximity to said crown, a slidable band in the form of an adjustable strap positioned against parts of the outer periphery of the front, back and sides of and free of direct connection throughout with the base of the crown and extending through all of said members, and a slide buckle bearing against a part of the outer periphery of one side of the base of said crown and slidably engaging with and having portions of its outer face permanently overlapped by the free end terminal portion of the strap extending in opposite directions for adjustably connecting the ends of the strap together to vary the length of that portion of the strap between the ends of the buckle to vary the size of the base of the crown and to bind said members and such portion of the strap against the outer periphery of the base of the crown.

In testimony whereof, I affix my signature hereto.

GEORGE W. MURPHY.
